United States Patent Office

Des. 195,530
Patented June 25, 1963

195,530

KNOB

John R. Morgan, Wheeling, Ill., assignor to Amerock Corporation, Rockford, Ill., a corporation of Illinois

Filed Dec. 13, 1962, Ser. No. 72,836

Term of patent 14 years

(Cl. D50—3)

FIG. 2 is a side view of the knob.

FIG. 3 is an enlarged perspective view of the knob.
FIG. 4 is an enlarged sectional view taken along the line 4—4 in FIG. 1.

I claim:

The ornamental design for a knob, substantially as shown.
